(No Model.)

F. MILLER.
WINDMILL.

No. 427,100.

Patented May 6, 1890.

UNITED STATES PATENT OFFICE.

FLORY MILLER, OF NAPOLEON, OHIO.

WINDMILL.

SPECIFICATION forming part of Letters Patent No. 427,100, dated May 6, 1890.

Application filed August 31, 1889. Serial No. 322,517. (No model.)

To all whom it may concern:

Be it known that I, FLORY MILLER, a citizen of the United States, residing at Napoleon, in the county of Henry and State of Ohio, have invented certain new and useful Improvements in Windmills; and I do hereby declare the following to be a full, clear, and exact description of the invention, such as will enable others skilled in the art to which it appertains to make and use the same.

My invention relates to improvements in windmills; and it has for its object, first, to provide means whereby the spindle which sustains the weight and strain of the wheel 15 and is subject to the greatest wear can be economically replaced when worn; second, to provide an improved turn-table for reducing the wear on the parts to a minimum and for enabling the wheel to turn with great ease, 20 and, finally, to simplify the construction and make the parts stronger and more durable.

With these ends in view, and such others as pertain to my invention, it consists of a horizontal rigid spindle which supports the 25 vertical wheel, and which is carried by the horizontally-turning tubular casting or body of the mill, said spindle being made in two longitudinal separable sections which are firmly fixed on the vertical tubular casting.

30 In practice the lower section or member of the horizontal spindle is made integral with the vertical tubular casting, while the upper member of the spindle is connected to the lower member by a lap-joint and bolted at its 35 inner end to the vertical tubular casting, the spindle being cylindrical in shape to adapt the wheel to turn thereon, as required. By making the spindle in two separate sections or members the upper member thereof, which 40 sustains the greater wear, can be easily removed and replaced at a very small expense.

My invention further consists in the peculiar construction and combination of parts, as will be hereinafter more fully described 45 and claimed.

In the accompanying drawings, Figure 1 is a side elevation of my improved windmill. Fig. 2 is a vertical longitudinal sectional view thereof, and Fig. 3 is a detail transverse sectional view through the spindle on the line x of Fig. 1.

Like numerals of reference denote corre-

sponding parts in all the figures of the drawings, in which—

1 designates the vertical casting, which is 55 made hollow to permit a vertical tubular mast 2 to be fitted therein. The base of this casting is enlarged or flanged, as at 3, and it rests on a series of friction wheels or rollers 4, which are journaled on shafts or pins 5, that 60 are secured in a turn-table or annular bearing 6, said bearing having a central circular boss 7, through which passes the mast 2. This tubular mast or post is fixed at its lower end to the usual crown of the ordinary tower 65 or derrick, and around said mast or post is fitted the annular bearing 6, which bearing may be firmly clamped to said mast by means of set-screws 8, which work in threaded apertures in the bearing and bind against the 70 mast. The tubular mast 2 serves to connect the vertical hollow standard to the tower and prevents the windmill from being carried away in a storm, and the annular bearing, with its friction wheels or rolls, serves to re- 75 duce the friction between the crown of the tower or derrick and the vertical standard 1, and enables the latter to turn freely in any horizontal direction.

At the upper end of the vertical hollow 80 standard I have provided a rigid bracket 10, having a central bearing 11 for the upper extremity of a tubular shaft 12, which serves to transmit the power to the pump or other machine at the base of the tower to be operated by the mill. This tubular shaft has secured to its upper end the driving-pinion 13, which meshes with a vertical master-gear 14, that is arranged at one side of the tubular hollow standard 1. This master-gear has a 90 series of radial integral spokes 15, to which the radial spokes 35 of the wheel 36 are fitted laterally and secured by means of through-bolts, the wheel being built up on the master-gear, which is thus rigidly secured to the 95 wheel, so as to rotate therewith and drive the pinion 13. This master-gear is fitted on a tubular horizontal shaft 16, which in turn is fitted on a rigid horizontal spindle 17, which is carried by the vertical standard 1, and projects outwardly at right angles therefrom. The tubular horizontal shaft 16 has an annular flange 18, that serves to confine the master-gear against lateral play on the tubular hori-

zontal shaft, and at its outer extremity said shaft is flared or enlarged to provide a mouth 19, in which is fitted a nut 20, that serves to prevent endwise play of the tubular hollow 5 shaft on the rigid spindle, said nut being fitted on the outer end of the spindle, and is detachably held in place on the spindle by a transverse pin 21, that passes through suitable apertures in the nut and spindle.

10 The wind-wheel 36 may be of any preferred construction, and it has a series of brace-rods 37, which extend from the radial spokes 35 of the wheel to the enlarged outer end or mouth 19 of the tubular horizontal shaft 16, said 15 brace-rods being rigidly secured to the spokes of the wheel and the hollow shaft, so that the wheel, the master-gear, and the tubular horizontal shaft all rotate or turn together. This cylindrical spindle is made in two longitudinal 20 parts or sections 22 22', the lower one of which is cast integral with the vertical tubular standard, and the other of which is detachably connected to the integral section by a lap-joint, the inner end of the upper removable 25 section or part being provided with a lateral flange 23, which fits against a corresponding flange 23, made integral with the standard and the lower section or member of the spindle, and through the flanges are passed bolts 23', one of which is shown in Fig. 2, whereby the upper section of the spindle is 30 removably secured to the lower section of said spindle and to the standard. By making the spindle in two parts one part can be removed when it has become worn by the 35 weight and friction of the wheel, and replaced by another part at a small expense.

On the opposite side of the vertical tubular standard from the master-gear are cast integral lugs 24, in which is fitted a vertical shaft 25, that forms the pivot of the bracket or casting 26 of the vane or tail, said bracket being fitted between the lugs, as shown in Fig. 2. The casting has longitudinal sockets 40 27 on one face thereof, in which sockets are received and secured the two longitudinal bars 27' of the vane or tail, (not shown,) and at its lower edge said casting or bracket is provided with a depending lug 28, which is 45 adapted to impinge against a rigid horizontal arm 29, cast integral with the base of the vertical tubular standard, the lug serving to limit the play of the vane in one direction. On the outer end of this rigid horizontal arm 50 55 is fitted a lever 30, the inner end of which is connected to the vane-casting by a link or rod

31, that passes through an eye 32 on said vane-casting. This lever is further provided with an adjustable regulating-weight 34, whereby the vane can be controlled, so as to be thrown out of the wind when the latter exceeds a certain pressure, and to the outer end of the lever is connected a cord or chain 40, which runs over a guide-pulley 41, that is journaled in the extreme upper end of the bracket on 60 the vertical tubular casting 1, said cord or chain extending thence to the ground, so that the lever can be operated at will.

The operation and advantages of my invention will be readily understood by those skilled in the art to which it relates from the foregoing description, taken in connection with the drawings.

Having thus fully described my invention, what I claim as new, and desire to protect by 75 Letters Patent, is—

1. In a windmill, the combination of a vertical standard, a horizontal cylindrical spindle having its lower section made integral with the standard and its upper section detachably secured to the standard and connected to the integral lower section by a lap-joint, a tubular shaft fitted on the cylindrical spindle and having its outer end provided with an enlarged hollow boss, a nut arranged 80 within the boss and fitted on the spindle to bear against the outer end of the tubular shaft, a master-gear carried by a tubular shaft and having a wheel erected thereon, and a driving-pinion which meshes with the 85 master-gear, substantially as described.

2. In a windmill having a vertical standard, the horizontal spindle consisting of two semi-cylindrical members, one of which is made integral with said standard and the other section detachably secured to the standard, as 90 and for the purpose described.

3. In a windmill, a vertical standard 1 and the horizontal spindle consisting of two semi-cylindrical members which are united to each 100 other by a lap-joint formed in the opposing faces thereof, the lower section of the spindle being made integral with the standard, and the upper section thereof being detachably secured at its inner end to the standard, substantially as described.

In testimony whereof I affix my signature in presence of two witnesses.

FLORY MILLER.

Witnesses:

JOSEPH GRIM,

GEORGE C. GERMAIN.
